UNITED STATES PATENT OFFICE.

ROSARIO COCO, OF BROOKLYN, NEW YORK.

DESIGN FOR A VOTIVE STAND.

61,010.

Specification for Design.

Patented May 30, 1922.

Application filed March 14, 1922. Serial No. 1,170. Term of patent 14 years.

To all whom it may concern:

Be it known that I, ROSARIO Coco, a citizen of the United States, residing in the borough of Brooklyn, in the city of New York, county of Kings, State of New York, have invented a new and ornamental Design for Votive Stands, of which the following is a specification, reference being had to the accompanying drawing, forming part thereof.

The figure is a perspective view of a votive-stand showing my new design.

I claim:

The ornamental design for a votive-stand, as shown.

Signed at New York city, this 10th day of March, 1922.

ROSARIO COCO.
